US00D819680S

(12) **United States Design Patent** (10) **Patent No.:** **US D819,680 S**
Nguyen (45) **Date of Patent:** ** *Jun. 5, 2018

(54) **DISPLAY SCREEN OR PORTION THEREOF WITH A GRAPHICAL USER INTERFACE**

(71) Applicant: **2236008 Ontario Inc.**, Waterloo (CA)

(72) Inventor: **Truc Nguyen**, Toronto (CA)

(73) Assignee: **2236008 Ontario Inc.**, Waterloo, Ontario (CA)

(*) Notice: This patent is subject to a terminal disclaimer.

(**) Term: **15 Years**

(21) Appl. No.: **29/540,300**

(22) Filed: **Sep. 23, 2015**

Related U.S. Application Data

(62) Division of application No. 29/439,988, filed on Dec. 18, 2012, now Pat. No. Des. 741,895.

(51) **LOC (11) Cl.** **14-04**

(52) **U.S. Cl.**

USPC **D14/487**

(58) **Field of Classification Search**

USPC D14/485-495

CPC G06F 3/0484; G06F 3/0485; G06F 3/0486

(57) **CLAIM**

The ornamental design for a display screen or portion thereof with a graphical user interface, as shown and described.

DESCRIPTION

The sole FIGURE shows a display screen or portion thereof with a graphical user interface.

The outermost broken line represents a display screen or portion thereof and forms no part of the claimed design. The remaining broken lines represent portions of the graphical user interface that form no part of the claimed design.

1 Claim, 1 Drawing Sheet
